UNITED STATES PATENT OFFICE.

HENRY C. COMBES, OF STALLO, MISSISSIPPI.

HAME.

1,127,190.

Specification of Letters Patent.

Patented Feb. 3, 1915.

Application filed June 17, 1914. Serial No. 845,583.

To all whom it may concern:

Be it known that I, HENRY CHARLIE COMBES, a citizen of the United States, and a resident of Stallo, in the county of Neshoba and State of Mississippi, have made certain new and useful Improvements in Hames, of which the following is a specification.

My invention is an improvement in hames, and has for its object to provide a device of the character specified, especially adapted for use in plowing, but suitable for any other purpose, and especially adapted to prevent the lines from becoming tangled or caught on the hames, either with a single draft animal, or a pair or more.

In the drawings: Figure 1 is a front view of a hame constructed in accordance with the invention, Fig. 2 is a partial view at right angles to Fig. 1, Fig. 3 is an enlarged section on the line 3—3 of Fig. 2, looking in the direction of the arrows adjacent to the line, and Fig. 4 is a vertical section through the bracket for engagement by the tug or trace hook.

The present embodiment of the invention comprises a pair of hames, but one of which is shown, since the members of the pair are constructed alike, but symmetrical in order that they may be used in pairs. Each hame comprises a body 1 of wood or the like, curved to shape, and approximately cylindrical in cross section. The ends of the body are reinforced with metal, the upper end having a ball 2 secured thereto, and the lower end having fitted thereover a socket 3 provided with an eye 4.

A ring 5 is connected with the eye 4 in the usual manner, and the said ring is adapted to receive the hame strap, for connecting the hame to the other member of the pair. On the outer face of the body and at the upper end three loops 6 are provided for receiving the upper strap, and to permit adjustment thereof. A ring 7 is connected with the body below the loops 6, by means of a staple 8. The ring 7 is for holding the reins of the bridle.

The above construction is the ordinary form of hame, and the invention resides in the mechanism for permitting the tug or trace to be connected with the hame. The said mechanism comprises a plate 9 having its side edges offset laterally from the body 50 of the plate in the same direction, to engage the outer face of the hame, and each of the

said side edges 10 is provided with openings 11 for receiving rivets 12 or the like, for securing the said side edges and the plate to the hame.

The plate 9 is provided at each end with longitudinally extending lugs 13 and 14 respectively, the lugs being perforated and offset in the same direction as the side edges, to fit against the body of the hame. Rivets 15 or the like are passed through the openings, and the said rivets assist the rivets 12 in holding the plate to the hame. The body portion of the plate is thus spaced away from the hame, so that there is some space between the body and the face of the hame.

The body is provided with a plurality of series of openings 16, the openings of each series being spaced apart from each other, and the openings of the series registering. The inner side edge of each opening is straight, as shown more particularly in Fig. 2, while the outer side edge is rounded. The openings are adapted for engagement by hooks 17 on a latch plate 18, and the latch plate is adapted for connection with the tug or trace.

The end of the plate is notched or recessed longitudinally to form the hooks, and the said hooks are spaced apart vertically from each other a sufficient distance to permit them to engage adjacent pairs of openings of the series. As shown in Fig. 2, each hook 17 engages a pair of registering openings, and the two hooks are so spaced that they may engage adjacent pairs of openings. Six openings are provided in each series, so that five positions of adjustment are permitted. The hooks are passed from one side of the plate to the other, being first engaged with the openings of the rearmost series, passing between the plate 9 and the body of the hame, and then out through the openings of the foremost series.

The latch plate is slotted longitudinally, as indicated at 19, and at its upper edge the plate is notched as shown at 20, the notch intersecting the slot 9. A latch 21 in the form of a hook is pivoted to the plate 18 in front of the slot 19 and the notch 20, as indicated at 22, and the bail of the hook is adapted to engage a loop 23 on the outer face of the latch plate in front of the notch 20.

A tug or trace is engaged with the latch plate, by passing the loop or eye at the front of the trace or tug, through the notch

20 and into the slot 19, the latch 21 being lifted before engaging the trace. After the trace has been engaged as above stated, the latch is arranged as shown in Figs. 2 and 3, the bill passing through the loop 23, and locking the eye of the tug or trace in the rear end of the slot 19. It will be noticed from an inspection of Fig. 2 that the slot 19 is of greater width at the end remote 10 from the hame than at the opposite end. There is no possible chance of accidental disengagement of the trace or tug, since the said trace or tug bears against that portion of the bill of the hook which extends 15 across the slot, and tends to lock the latch plate in closed position. There are no projecting lugs or the like for engagement by the line, and the tug may be adjusted vertically with respect to the hame to bring 20 the pressure exerted by the draft on any part of the animal's shoulder. With chain traces, they may be adjusted in length, merely by engaging different hooks with the hook of the latch plate. The lug 14 holds a 25 ring 24 in place, the said ring being at the lower end of the plate.

I claim:

1. In a hame, a plate for connecting a

trace or tug to the hame, said plate having means at one end for engaging the hame 30 and having at the other a hook for engagement by the trace or tug, and a latch pivoted to the plate and extending across the space between the body and the bill of the hook, and having an angular portion adapt- 35 ed to extend across the hook at approximately a right angle to the body of the latch, the plate having at the bill of the hook a loop through which the angular portion of the latch passes.

2. In a hame, a plate for connecting a trace or tug to the hame, said plate having a longitudinally extending hook at one end for connection with the trace or tug and having a latch pivoted to the plate and 45 adapted to extend across the space between the body of the plate and the bill of the hook, the bill of the hook having a loop, and the latch having an angular portion adapted to pass through the loop and ex- 50 tending across the hook.

HENRY C. COMBES.
